UNITED STATES PATENT OFFICE.

WILLIAM N. REYNOLDS, OF LITCHFIELD, CONNECTICUT.

RAIL-LOCK AND TIE-PLATE.

No. 886,248.

Specification of Letters Patent.

Patented April 28, 1908.

Application filed August 6, 1907. Serial No. 387,314.

To all whom it may concern:

Be it known that I, WILLIAM N. REYNOLDS, a citizen of the United States, and a resident of Litchfield, in the county of Litchfield and State of Connecticut, have invented a new and useful Improvement in Rail-Locks and Tie-Plates, of which the following is a full, clear, and exact description.

The purpose of the invention is to provide a combined lock and tie plate for railway rails, of simple, durable and economic construction, adaptable to any form of sleeper, and which will effectually prevent the rails from spreading or having any lateral movement, thus providing for a safe and regular line of tracks even where the roadbed is steep.

The invention consists in the novel construction and combination of the several parts as will be hereinafter fully set forth and pointed out in the claims.

Reference is to be had to the accompanying drawings forming a part of this specification in which similar characters of reference indicate corresponding parts in all the figures.

Figure 1 is a side elevation of the sleeper or tie, a section or side elevation of the device, and a transverse section through the rails held thereby, the section being taken practically on the line 1—1 of Fig. 2; Fig. 2 is a plan view of the sleeper or tie shown in Fig. 1, and parts carried thereby; Fig. 3 is an enlarged plan view of one end of the tie plate; Fig. 4 is an enlarged bottom plan view of an outer member of the rail lock; and Fig. 5 is an enlarged bottom plan view of the inner member of the rail lock.

A represents a tie or sleeper ordinarily employed in railroad construction; B represents a tie plate that is adapted to rest upon the said sleeper, and to extend practically the length thereof, being secured in its central portion to the sleeper by bolts or spikes 10, or their equivalents, and by other means to be hereinafter mentioned.

C represents the rails which cross the tie plate B in the customary manner.

The tie plate B is made thicker at its end portions than at any other portion in its length, as is shown at 11 in Figs. 1 and 3, and in consequence transverse shoulders 12 are formed a convenient distance from the ends of the said tie plate. Between the shoulders 12 and the ends of the tie plate, adjacent the end, a group, usually of four apertures 13 is provided, and about centrally within this

group a recess 14 is made; in the upper face of the tie plate at each end and adjacent each shoulder 12, usually two apertures 13^a are produced. Further inward or about the center of the tie plate adjacent each end, a set of two apertures 15 is provided corresponding to the apertures 13^a, and the flanges of the rails lie between these two sets of apertures 13^a and 15, which are transversely located on the tie plate. In Fig. 3 I have shown an aperture as centrally located between those designated as 15, but such aperture is not important and may be omitted, but between the apertures of each set, recesses 16 and 16^a are produced in the upper face of the tie plate for a purpose to be hereinafter described, and between these recesses 16 and 16^a but slightly to the rear thereof, ordinarily two longitudinally arranged apertures 17 are produced.

The rail lock is made in two sections, a brace D, which is an outer section, and the guard section D', which is an inner section, and a rail lock is provided for each rail. Each brace section consists of a base plate 18 provided with four apertures 19 that correspond to the apertures 13 hereinbefore mentioned, and about centrally between the apertures 19 on the base plate 18, a lug 20 is formed, and when the brace section is laid upon the thicker portion of the tie plate B, the lug 20 enters and fits in the recess 14 at said thicker portion of the plate, as is clearly shown in Fig. 1. An arm 21 extends centrally from the upper face of the base 18 of the brace section, and the said arm 21 is given an upward and an inward inclination and terminates in quite a wide head 22 that has a recess 23 produced in its inner edge, and the said recess 23 when the brace section is in position receives a portion of the outer face of the tread of the rail and the under portion of said face, as is clearly shown in Fig. 1. The brace section is secured to the tie plate and likewise to the tie or sleeper, by means of spikes 24 driven through the apertures 19 in the brace section and the apertures 13 in the tie plate, and it may be here remarked that the flanges of the rails are secured to the tie plate by means of spikes 25 and 25^a in the customary manner, which spikes are passed through the apertures 13^a and 15 of the tie plate.

Each guard section D' consists of a flat plate 26, having one of its ends 27 enlarged, so that the plate is practically in the form of

a T, and at the enlarged or head end 27 of the guard plate D', two lugs 28 are produced upon its under face, and these lugs are adapted to enter the recesses 16 and 16^a in the tie plate above referred to; and in the body portion of the guard section D', longitudinal apertures 31 are produced that register with the apertures 17 when the guard plate is in position, and suitable spikes 30 pass through 10 these apertures into the tie or sleeper and serve to hold the tie or sleeper in position.

In Fig. 5 I have illustrated the head portion of the guard section as provided with a recess 29 about centrally produced in its bearing edge; this recess is not absolutely essential, but is intended to receive a spike 32, for example, to engage with the flange of the rail in the event the spikes could not be driven as ordinarily adjacent the edges of the tie. When a guard section is in position on the tie plate B it engages with the inner edge of the flange of the rail, and since the brace section has perfect bearing against the outer face of the tread of the same rail, the edges 20 of the rails are effectually prevented from shifting laterally under any conditions, especially so since they are assisted by the tie plate B and its peculiar construction.

Having thus described my invention, I claim as new and desire to secure by Letters 30 Patent,

1. In railway construction, a tie plate adapted for attachment to a sleeper, having bearings for the outer edges of the rail flange 35 the tie plate being provided with transversely arranged apertures adapted to receive fastening devices for securing the outer and inner edges of the flanges of the rails to said tie plate, and rail locks, which locks include brace 40 sections and a guard section, both having interlocking engagement with the tie plate, the brace section engaging with the outer face of the head of the rail, and the guard section with the inner edge of the flange of 45 the rail.

2. In railway construction, a tie plate adapted for attachment to a sleeper and having transverse shoulders for engagement with the outer edge of the flanges of the rails, the tie plate being provided adjacent to the shoulders with a set of transversely arranged apertures, and also having a second set of transverse apertures between the said shoulders and the center of the tie plate, the said 50 apertures being adapted to receive fastening devices for securing the inner and outer edges of the flanges of the rails to said tie plate, and locking devices for the rails, each comprising an outer brace section and an inner guard 55 section, each section having an interlocking connection with the tie plate, and auxiliary locking means, the brace sections consisting each of a base plate and an arm extending therefrom adapted for engagement with the 60 outer side and the under face of the tread of 65

the rail, the engaging end of said arm being of less width than the space between the said apertures adjacent to the shoulders and extending over said space, the guard section consisting of a flat plate adapted for engagement with the inner edge of the flange of the rail, the engaging end of said guard section extending between the said second set of transversely arranged apertures.

3. In railway construction, the combination with a tie plate having transverse shoulders produced therein adjacent its ends and a recess between the said shoulders and the ends of the plate, and recesses between the center of the plate and the said shoulders, the tie plate being further provided at each end portion with a set of transversely arranged apertures in line with the last mentioned recesses, and a set of transversely arranged apertures adjacent to the said shoulders, the flanges of the rails lying between the said sets of apertures and the sets of apertures being adapted to receive fastening devices to secure the flanges of the rails to said tie plate, of a lock for the rails, which lock consists of a 90 brace section and a guard section, each brace section comprising a base plate having a lug upon its under face adapted to enter a recess in the tie plate adjacent an end thereof, and an arm that extends upwardly and inwardly from the base plate, terminating in a wide head having a groove in its inner edge, which groove receives a portion of the outer side face of the tread of the rail and adjacent portion of the under face of the said tread, 100 each guard section consisting of a flat T plate, its wider or head portion having lugs formed upon its under face at the outer end thereof and adapted to enter the recesses in the tie plate located between the shoulders of said 105 plate and its center, the outer edge of the head of a guard section engaging with the inner edge of the flange of the rail, and means for securing the two sections to the said tie plate, auxiliary to the aforesaid lugs.

4. In railway construction, a tie plate adapted for attachment to a sleeper and having transverse shoulders for engagement with the outer edges of the flanges of the rails, and locking devices for the rails each 115 comprising an outer brace section engaging with the outer face of the head of the rail, and an inner guard section, the guard sections each comprising a flat plate having one of its ends enlarged forming a head adapted 120 to engage the inner edge of the flange of the rail, the said head being provided on its under face at the outer end thereof with spaced lugs, and the body portion of the plate being provided with longitudinally arranged apertures, the said tie plate having recesses in its upper face adapted to receive the said lugs, the tie plate being provided with longitudinally arranged apertures 125 adapted to register with the apertures in the 130

- body portion of the guard section for the passage of fastening means, the tie plate being further provided with transverse apertures in line with the said recesses and between 5 which the head of the guard section extends, the said apertures at each side of the head of the guard section being adapted to receive spikes to secure the inner edge of the flange of the rail to the tie plate.
- 10 5. In railway construction, a tie plate adapted for attachment to a sleeper and having transverse shoulders for engagement with the outer edges of the flanges of the rails, the said tie being provided with trans- 15 versely arranged apertures adjacent to the shoulders, a group of apertures between the shoulders and the ends of the tie plate, and a recess formed in the tie plate centrally of the group of apertures, and locking devices 20 for the rails comprising an outer brace section engaging with the outer face of the head of the rail, and an inner guard section engaging with the inner edge of the flange of the rail, the brace sections each comprising a base 25 plate adapted to rest on the tie plate and when in position being spaced at its inner end from the said apertures adjacent to the shoulder

of the tie plate, the base plate being pro- 30 vided with apertures corresponding with the group of apertures in the tie plate for the passage of fastening means, the said base plate having a lug upon its under face adapt- 35 ed to enter the recess in the tie plate, an arm extending upwardly and inwardly from the base plate and having a head at its free end 40 provided with a groove in its edge adapted to receive a portion of the outer side face of the tread of the rail and the adjacent portion of the under face of said tread, the said head extending beyond the inner end of the 45 base plate and located above the space between the said apertures adjacent to the shoulder of the tie plate, the said last mentioned apertures being adapted to receive spikes to secure the outer edge of the flange of the rail to the said tie plate.

In testimony whereof I have signed my name to this specification in the presence of two subscribing witnesses.
